UNITED STATES PATENT OFFICE

SYLVESTER LEO. GOOKIN, OF QUINCY, MASSACHUSETTS, ASSIGNOR TO UNITED SHOE MACHINERY CORPORATION, OF PATERSON, NEW JERSEY, A CORPORATION OF NEW JERSEY

FASTENER SUPPLYING APPARATUS

Original application filed July 21, 1930, Serial No. 469,432. Divided and this application filed July 23, 1931. Serial No. 552,698.

This invention relates to machines for inserting fasteners and more particularly to means for supplying fasteners to the mechanism for inserting them. The invention is 5 herein illustrated as embodied in a form designed especially for supplying eyelets in a duplex eyeleting machine but in certain aspects the invention is not limited to machines of the duplex type nor to eyelets as the

10 fasteners to be supplied. Nevertheless, for convenience in setting forth the novel features of the invention, the latter is herein described in terms relating to duplex eyeleting machines. The subject-matter of the invention 15 has heretofore been illustrated and described in my copending application for improvements in fastener-inserting machines, Serial No. 469,432, filed July 21, 1930, of which the present application is a division.

20 In duplex eyeleting machines, one of the chief requirements is to insure feeding the eyelets into each of the divisions of a duplex raceway at a rate no less than the rate at which the eyelets are removed from the delivery end of the raceway. Experience has demonstrated that to insure an even and sufficiently rapid rate of emission of eyelets from a hopper the eyelets should stand with their flanged ends on an inclined supporting 25 surface while passing through an emission port in an upstanding wall of the hopper. The importance of these conditions of emission has been recognized even to the extent of adopting costly and cumbersome expedients 30 in duplex raceway construction solely for the purpose of reversing the emitted eyelets in one of the series as they travel along their division of the raceway. Even though these expedients have been costly and cumbersome, 35 they have been preferable to simpler and less costly constructions in which uniformity of the conditions of emission has been sacrificed by arranging the emission ports for one of the series of eyelets so that their relative inversion must occur before emission.

40 With regard to the conditions last explained, still another object of the invention is to provide for emission of two series of eyelets from a hopper under the most favorable 45 conditions, identical as to both series, without

requiring inversion of the emitted eyelets of one series to bring about ultimate opposed relationship of those eyelets to the eyelets in the other series.

50 A novel feature relating to this aspect of the invention consists in an eyelet-hopper having two oppositely inclined bottom walls and outlet ports formed and arranged to emit eyelets, and only those eyelets, that stand on said walls in one certain relation thereto, 55 means for feeding such eyelets through the ports, and a duplex raceway the divisions of which are arranged to conduct into parallel opposed relationship the eyelets so emitted. Preferably, as herein shown, the upper portions 60 of the divisions of the raceway diverge upwardly and are equally though oppositely inclined, as are the bottom walls of the hopper which is arranged between and connects the aforesaid upper portions. Moreover, as shown, the emission ports are formed 65 in cylindrical walls of the hopper which converge upwardly from the bottom walls and merge one into the other to form one mouth into which the supply of eyelets may be 70 poured. The opposite inclinations of the upper portions of the divisions of the raceway and the corresponding inclination of the axes of the eyelets when emitted avoids 75 the necessity of inverting any of the emitted eyelets, since all that is required to bring about parallel but opposed relationship of the eyelets of one series to those of the other series is a short simple bend in one of the divisions of the raceway to reverse the direction of the inclination or pitch of the eyelets 80 of one series.

85 Referring to the drawings,

Fig. 1 is a left-side elevation of a duplex eyelet-inserting machine provided with eyelet-supplying means constructed in accordance with this invention;

Fig. 2 is a left-side elevation, partly in section, of a duplex eyelet-hopper, a duplex raceway and related operating mechanisms 95 included in Fig. 1;

Fig. 3 is a top plan view projected from Fig. 2 showing a portion of the raceway and mechanism for operating the delivery end thereof;

Fig. 4 is a top view, partly in section, of a latching device by which the raceway may be detachably secured to the frame of the machine;

5 Fig. 5 is a sectional view in a vertical plane of the structure at the lower right of Fig. 2;

Fig. 6 is a vertical section through the hopper in a plane indicated by line VI—VI on Fig. 2;

10 Fig. 7 is a view showing the hopper in elevation and the raceway in cross-section as indicated by line VII—VII of Fig. 2;

Fig. 8 is a vertical sectional view of the hopper in a plane extending from front to 15 rear; and

Fig. 9 is a perspective view of the upper portion of one of two similar links for operating the hopper brushes respectively.

Although, for the purpose of setting forth the features of the fastener-supplying means that constitute the essence of this application, it will not be necessary to include a complete description of the machine illustrated in Fig. 1, a brief outline of the general organization 225 of that machine follows.

The main frame 20 is hollow and encloses various pulleys, cams, levers and other movable parts, but is open at the front which is at the right-hand side of Fig. 1. The flat base 21 of the frame is adapted to stand on a bench. A stationary shaft 22 mounted in the frame supports two idle pulleys, one of which is represented at 23, over which a driving belt 24 runs to impart rotation to a receiving pulley 25 of a disengageable clutch. Upper and lower bearing members 26 enclosed in the frame 20 and bolted thereto provide bearings for a cam-shaft 27 on which the aforesaid clutch is mounted. The operation of the clutch is controlled by a sliding pin or bolt 28 which may be retracted by a treadle-chain and moved toward the clutch by a spring (not shown).

Two opposed punches 32 are arranged in alignment with each other to punch fastener-receiving holes simultaneously in the two quarters of a shoe-upper. The punches are carried by plungers arranged to slide in bearings formed in the arms of a U-shaped frame 33 that receives two distinct motions, one from front to rear immediately after the punches have been retracted from the punched holes, and the other from right to left immediately after fasteners have been inserted and clenched in the holes; the purpose of the latter motion being to impart a step of feeding movement to the work and thereby space successive fasteners one from another. The outer ends of the punching plungers are provided with heads 34 which are engaged by strikers 99 carried by operating levers 96. These levers are mounted on fulcrum pins 97 and receive their operating motions from a single mechanism (not shown) actuated by cams 105 and 106.

The U-shaped frame 33 is also provided with bearings for two opposed and aligned fastener-inserting devices 43 the heads 47 of which are initially out of register with the strikers 99. The punching devices 32 and the fastener-inserting devices 43 are operated alternately by the strikers 99 with which they are placed in register by the forward and backward shifting of the frame 33 as derived from cams 59 and 60.

Sidewise movements of this frame for feeding the work are derived from cams 81 and 82 and communicated by intermediate parts including a lever 77. Retraction of the fastener-inserting devices is caused by light levers 49 connected by a tension spring 50. In like manner, the punching devices are retracted by spring-stressed levers.

The quarters of a shoe-upper are inserted between presser-feet 65 and an intermediate stationary work-support 64. Moreover, an intermediate tongue 55 carried by the frame 33 is provided with an embedded double-ended punch-bed (not shown) and an embedded double-ended fastener-upsetting anvil (not shown).

The mechanism above described operates as follows: the parts stand in the positions represented in Fig. 1 at the beginning of each cycle. First, the strikers 99 operate the punching devices 32 and immediately recede. Next, the frame 33 moves to the rear, thereby placing the fastener-inserting devices 43 in register with the punched holes and also in register with the strikers 99.

Now, the strikers operate the fastener-inserting devices to which fasteners are presented by means hereinafter described, but the strikers dwell while the devices 43 are held thereby against the fasteners just inserted. During this dwell the frame 33 is moved from right to left, the work thus receiving a step of feeding movement from the devices 43. Finally, the strikers 99 and the devices 43 recede, and the frame 33 returns to its initial position.

The present invention provides improved means for supplying eyelets to the fastener-inserting devices 43. The illustrated fastener-supplying means comprises a duplex hopper 115 (Figs. 1 and 2) and a duplex raceway, the individual divisions of which are indicated at 116 and 117, respectively. These elements and others by which they are connected and braced constitute a detachable unit which may be readily mounted on the frame 20 and detached therefrom with very little loss of time. Consequently, a plurality of detachable raceway units containing eyelets of different sizes, different colors or other characteristics may be readily interchanged in accordance with the requirements of successive lots of work.

The divisions 116 and 117 of the raceway are parallel to each other except their upper

portions which diverge upwardly and lie in planes that diverge upwardly, the parallel portions being rigidly connected to each other in confronting relation by interposed 5 spacing blocks 118 and screws 119. Moreover, the lower section of the raceway is movable to present the eyelets to the fastener-inserting devices, whereas the upper section and the hopper 115 are stationary. The two 10 sections have an articulate pivotal connection which includes a coupling member designed to cooperate with a complementary coupling member permanently attached to the frame 20 and forming a part of the operating 15 mechanism by which the delivery end of the raceway is moved to and fro. The construction is such that the act of mounting any one of a plurality of detachable raceway units on the means provided for that 20 purpose also results in coupling the movable section of the raceway to the raceway operating mechanism, no additional act or operation being required to establish the desired connection or relation of the movable 25 section and the operating mechanism.

The raceway is supported in its operative position by two parallel dowel studs 120 projecting horizontally from the left-hand side of the frame 20. The two spacing blocks 30 118 are bored to receive the dowel studs as shown in Fig. 4. Interconnected latches 121 mounted on the frame 20 and connected thereto by pivot pins 122 are arranged to snap over outer edges of the blocks 118 and thereby maintain the raceway firmly against the frame 20. The latches are connected by a tension spring 123 which maintains them normally in latching position. The latches are also connected by a pin-and-slot connection 35 124 whereby the movements of one are communicated to the other. A knob 125 is formed on one of the latches to provide convenient means by which the latches may be retracted to release the raceway.

40 The pivotal joint by which the stationary section and the movable section of the raceway are connected comprises coaxial pivot pins 126 and 127 (Fig. 5). The axis of these pins intersects the channels 128 of the two 45 divisions of the raceway (see Fig. 3) but the pins are spaced apart to clear the lower division so that the eyelets in that division may cross the axis of the joint without interference. A spacing block 129 interposed between the two divisions of the movable section of the raceway is connected to the adjacent stationary block 118 by the pivot pin 50 126, while a reinforcing block 130 affixed to the lower side of the movable section is connected to a stationary reinforcing member 55 131 by the pivot member 127. The blocks 129 and 130 and the two divisions of the movable section are all rigidly clamped to each 60 other by bolts 132, while the reinforcing 65

member 131 is affixed to the stationary section of the raceway by screws 133.

The pivot pin 127 is pinned to the block 130 and is utilized to communicate oscillatory motion to the movable section. For 70 this purpose a radially extending tongue 134 is formed on the lower end of this pivot member. The tongue 134 constitutes one element of a tongue-and-groove coupling, the complementary groove of which is formed in a 75 head 135 of a rock-shaft 136. The rock-shaft is journaled in a boss 137 formed on the frame 20 and is provided with an arm 138 by which it may be oscillated.

The mechanism for operating the movable 80 section of the raceway is shown in Fig. 3. A cam 139 carried by the cam shaft 27 cooperates with a cam-roll 140 carried by a lever 141. The lever is mounted on the fulcrum rod 63 and is held against the cam by a tension spring 142. A link 143 communicates motion from the lever 141 to the arm 138 to oscillate the movable section of the raceway.

When the parts are in their initial positions as shown in Fig. 3, the tongue and 90 groove of the coupling 134, 135 are parallel to the dowel studs 120. Consequently, when a raceway is being mounted on or demounted from the dowel studs by movement lengthwise of the latter, the tongue 134 slides into 95 or out of the groove in the head 135, as the case may be, and when the raceway is caught by the latches 121 and thereby held against the outer surface of the frame 20 the pivot pins 126 and 127 of the raceway are maintained in coaxial relation to the rock-shaft 136. Moreover, the dowel studs 120 maintain the tongue 134 in the groove member 135 and thus preserve the coupled relation 100 of the raceway and the operating mechanism.

In duplex eyeleting machines in which both eyelets of a pair are inserted by movement toward each other, it is necessary to deliver the two eyelets in relatively reverse 110 positions. That is, the barrels of the eyelets must be toward each other and the flanges must be away from each other. Moreover, when two series of eyelets are to be delivered respectively to the fastener-inserting devices of a duplex machine, it is desirable to supply them under identical 115 conditions to insure equal replenishment of the two series. With regard to duplex raceways that receive both series of eyelets from a common mass stored in a hopper, equality in the feeding of the two series has constituted one problem, and the delivery of the eyelets in relatively reverse positions has constituted another problem. For example, in some prior constructions the eyelets of one series have been obliged to stand with their flanges at their upper ends to be fed out of the hopper while the eyelets of the other series have been obliged to stand with their flanges 120 125 130

at their lower ends to be fed out. In such cases, the feeding conditions of the two series have been dissimilar and the rate of feeding has therefore been unequal.

5 In other prior constructions the eyelets of the two series have stood in the same position in a common inclined plane while being fed from the hopper, but their delivery from the hopper has been at opposite sides of the 10 axis of a rotary brush or feeding member. Under these conditions the eyelets delivered from one side of the hopper have been propelled by downward inclined movement of the brush into the mass of eyelets while those 15 delivered from the opposite side of the hopper have been propelled by upward inclined movement of the brush out of the mass. Here again, the feeding conditions have been dissimilar and the rate of feeding has therefore 20 been unequal.

With a view to supplying two series of eyelets under similar conditions and with equal rates of feeding from a common mass in a hopper to a duplex raceway, the present 25 invention provides an improved construction which, at the same time, causes the eyelets of the two series to be equally but oppositely inclined as they pass through the outlets from the hopper to their respective 30 divisions of the raceway.

As shown in Figs. 1 and 2, the lower division 117 of the raceway is all in one inclined plane, while the movable section and the lower portion of the stationary section of the 35 upper division 116 are likewise all in one inclined plane parallel to the plane of the division 117. The upper portion 145 of the division 116 and the corresponding portion of the division 117 diverge upwardly and are 40 not only oppositely inclined but have equal steepness or slant. A transverse bend 146 in the division 116 provides for the divergence and parallelism mentioned above.

The shape of the hopper 115 resembles that 45 of a funnel although its mouth 147 is preferably oblong rather than circular. This formation facilitates filling the hopper without spilling any eyelets. Its bottom walls 148 (Fig. 8) are flat and oppositely inclined and 50 converge downwardly, their angles of inclination being equal. These walls are screwed against the lower ends of annular walls 149 by which the massed eyelets in the hopper are localized adjacent to two feeding brushes. 55 The walls 148 are bored to provide bearings for oppositely inclined shafts 150 which extend through them. Each shaft carries a brush 151 at its inner end and a ratchet-wheel 152 at its outer end and each is provided with 60 an oscillatory pawl-carrier 153 loosely mounted thereon between the ratchet-wheel and the adjacent wall 148. Each pawl-carrier 153 carries an operating pawl 154 (see Fig. 7) and a leaf-spring 155 by which the 65 pawl is held against the ratchet-wheel. The

pawl is connected to the pawl-carrier by a pivot member 170.

The annular walls 149 of the hopper are provided with notches 156 through which the barrels of the eyelets may pass, the teeth between the notches being spaced from the bottom walls 148 sufficiently to clear the flanges of the eyelets that stand with their flanged ends on the wall 148. Each series of notches 156 forms communication from the interior 75 of the hopper to a division of the raceway (see Fig. 7). Each of the brushes 151 is rotated in a direction that causes upward travel of the tufts as the latter sweep the correctly positioned eyelet through the 80 notches or outlets 156, the conditions under which the eyelets are fed out of the hopper being therefore similar with respect to the two divisions of the raceway.

The illustrated mechanism for operating the brushes 151 receives motion from the lower hammer 96 (see Fig. 2). An extension arm 158 rigidly related to the hammer communicates motion through a link 159 to a bell-crank lever 160. This lever is mounted on the frame 20 by a fulcrum or pivot pin 161. Two links 162 communicate the to-and-fro movements of the bell-crank lever to the pawl-carriers 153, respectively. The pivot pins 163 by which these links are connected to the bell-crank lever are located at points ninety degrees from each other with respect to the axis of the fulcrum 161, and the links are arranged in crossed relation so that when 90 one of them is being moved upwardly the other will be moved downwardly. Thus, the brushes 151 will be operated alternately.

The upper ends of the links 162 are preferably formed to provide for quickly attaching them to and detaching them from the pawl-carriers so that the operation of detaching one raceway unit and attaching another may be facilitated.

Accordingly, each of the links is provided 100 with a connecting stud 164 permanently affixed thereto, as shown in Fig. 9. The stud is provided with a circumferential groove 165 adapted to receive the inner end of a detent 166 (see Fig. 7), the detent being carried by a leaf-spring 167 attached to the pawl-carrier and normally projected into a socket 168 formed in the pawl-carrier for the reception of the stud 164. The leaf-spring 167 is extended a short distance beyond the 110 detent to provide a finger-piece by which the detent may be retracted to release the stud 164 whenever it is desired to disconnect the link 162 from the raceway structure.

Having thus described the invention, what I claim as new and desire to secure by Letters Patent of the United States is:

1. In a duplex eyeleting machine, an eyelet-hopper having two oppositely inclined bottom walls and upstanding walls in which 120 outlet ports are formed and arranged to emit 130

- eyelets, and only those eyelets, that stand on said bottom walls respectively in one certain relation thereto, means arranged to feed eyelets through said ports, and a duplex raceway 5 the divisons of which are arranged to conduct into parallel opposed relationship the eyelets so emitted.
2. In a duplex eyeleting machine, an eyelet-hopper having two oppositely inclined 10 bottom walls and cylindrical walls extending upwardly from said bottom walls respectively, said cylindrical walls having outlet ports formed and arranged to emit eyelets, and only those eyelets, that stand on said 15 bottom walls respectively in one certain relation thereto, rotatable eyelet brushes arranged to sweep eyelets through said ports, mechanism arranged to operate said brushes, and a duplex raceway the divisons of which 20 are arranged to conduct into parallel opposed relationship the eyelet so emitted.
3. In a duplex eyeleting machine, an eyelet-hopper having two oppositely inclined 25 bottom walls and oppositely inclined cylindrical walls extending upwardly from said bottom walls respectively, said cylindrical walls having outlet ports formed and arranged to emit eyelets, and only those eyelets, that stand on said bottom walls respectively 30 in one certain relation thereto, rotary brushes arranged to sweep eyelets through said ports, mechanism arranged to operate said brushes, and a duplex raceway the divisons of which are arranged to conduct into 35 parallel opposed relationship the eyelets so emitted.
4. In a duplex eyeleting machine, an eyelet-hopper having two oppositely inclined bottom walls and oppositely inclined cylindrical walls extending upwardly therefrom, 40 rotatable eyelet-brushes arranged above but adjacent to said bottom walls respectively, the axes of said brushes being oppositely inclined, mechanism for turning said brushes, said cylindrical walls having outlet ports adjacent 45 to the upwardly moving portions of said brushes respectively, and said ports being formed and arranged to emit eyelets, and only those eyelets, that stand on said bottom 50 walls respectively in one certain relation thereto, and a duplex raceway arranged to conduct into parallel opposed relationship the eyelets so emitted.
5. In a duplex eyeleting machine, a funnel-shaped eyelet-hopper having two oppositely inclined flat bottom walls that converge 55 downwardly and two oppositely inclined cylindrical walls that converge upwardly from said bottom walls respectively and merge one into the other, said cylindrical walls having outlet ports formed and arranged to emit eyelets that stand on said bottom walls respectively, means arranged to sweep eyelets 60 through said ports, and a duplex raceway the 65 divisons of which are arranged to conduct eyelets emitted through said ports.
6. In a duplex eyeleting machine, an eyelet-hopper having two angularly related bottom walls and outlet ports arranged to emit 70 eyelets lying on said walls respectively, two brushes arranged to sweep eyelets through said ports, said brushes being arranged to turn about angularly related axes, and brush-operating mechanism comprising links operatively connected to said brushes respectively, and an oscillatory actuating member to which both of said links are connected and by which they are reciprocated to operate said brushes.
7. In a duplex eyeleting machine, a duplex raceway the divisons of which confront each other and have oppositely inclined upper portions that lie in upwardly divergent planes, a hopper arranged between and connecting said oppositely inclined portions, said hopper having outlet ports formed and arranged to emit oppositely inclined eyelets to said portions respectively and said ports being similarly related to said portions respectively to render alike the conditions of emission to 80 both of said portions, and means arranged to stir the eyelets in said hopper.
8. In a duplex eyeleting machine, a duplex raceway the divisons of which have equally but oppositely inclined upper portions that 85 diverge upwardly, a duplex hopper arranged between and connecting said portions, said hopper having oppositely inclined bottom walls in cooperative relation to said portions respectively and having outlet ports arranged to 90 emit eyelets to said portions respectively, and means arranged to stir the eyelets in said hopper.
9. In a fastener-inserting machine, a hopper having two oppositely inclined bottom walls and oppositely inclined side walls extending upwardly therefrom, rotatable brushes arranged to sweep fasteners upwardly on said bottom walls, said side walls having outlet ports formed and arranged to emit 95 fasteners, and only those fasteners, that stand on said bottom walls respectively in one certain relation thereto at points where the fasteners are swept upwardly by said brushes, means arranged to operate said brushes, and means arranged to conduct the emitted fasteners from said ports to points of delivery.
10. In a duplex fastener-inserting machine, a frame, a duplex raceway the divisons of which comprise confronting portions spaced apart and secured to interposed connecting means, said frame and said connecting means being provided with complemental dowels and sockets by which to mount the raceway, and means arranged to secure the raceway so 110 mounted.
11. In a duplex fastener-inserting machine, a frame, a duplex raceway the divisons of which comprise confronting portions spaced apart and secured to interposed connecting 115 means.

means, said connecting means having dowel-holes extending transversely between the divisions of the raceway and said frame being provided with dowels projecting horizontally 5 to enter said holes, and means arranged to secure the raceway on said dowels.

12. In a duplex fastener-inserting machine, a frame, a duplex raceway the divisions of which comprise confronting portions spaced 10 apart and secured to interposed connecting members, said members being spaced apart lengthwise of the raceway and having dowel-holes extending transversely between the divisions of the raceway, raceway-supporting 15 dowels secured to and projecting horizontally from said frame to enter said holes, and means mounted on said frame to engage the raceway and thereby secure it in an operative position on said dowels.

20 13. A duplex fastener-supplying unit comprising a duplex raceway the divisions of which have upper portions that lie in upwardly divergent planes and lower portions that lie in confronting relation, means interposed 25 between and connecting said confronting portions, and a hopper arranged between and connecting said upper portions, said hopper having outlet ports arranged to emit fasteners to said upper portions respectively, and said 30 interposed connecting means having provision for mounting said unit on supporting means of a duplex fastener-inserting machine.

14. In a duplex fastener-inserting machine 35 provided with mechanism arranged to insert fasteners in opposed relation, a duplex raceway arranged to supply fasteners in opposed relation to said mechanism, the divisions of said raceway having portions that lie in upwardly divergent planes, and a hopper arranged 40 between said portions and having outlet ports arranged to emit fasteners to said portions respectively.

15. In a fastener-inserting machine having 45 a frame and fastener-inserting mechanism arranged therein, a detachable raceway for supplying fasteners to said mechanism, said raceway and said frame being provided with cooperative dowels and sockets by which 50 to mount the raceway in cooperative relation to said mechanism, and a plurality of retaining devices movably attached to said frame and arranged to operate automatically to fasten spaced portions of the raceway in certain 55 predetermined positions.

16. In a fastener-inserting machine having a frame and fastener-inserting mechanism arranged therein, a detachable raceway for 60 supplying fasteners to said mechanism, said raceway and said frame being provided with cooperative dowels and sockets by which to mount the raceway in cooperative relation to said mechanism, and a plurality of retaining devices movably attached to said frame 65 and interconnected with each other to partake

in common of operating movement, said devices being arranged to fasten spaced portions of the raceway in certain predetermined positions.

In testimony whereof I have signed my 70 name to this specification.
